Machine Corporation, Fort Wayne, Ind., a cor-
poration of Indiana

Application January 21, 1935, Serial No. 2,695

10 Claims. (Cl. 101—123)

The invention relates to machines by which to impress paint and other fluids in predetermined patterns or arrangement on paper and other material that is fed to the machine.

5 In recent years there has been developed a method of producing advertising matter, posters, catalogs and other matter in which designs, patterns, figures, letters, etc., are formed on paper, paper board or other material by the use of stencil screens.

The screen is formed of silk, copper wire, organdie or other suitable materials and the design is formed thereon. The screen is blocked off or made temporarily or permanently impervious except in the portion or portions thereof through which an intended impression is to be made on the sheet of stock that is beneath the screen.

Generally the material has been forced through the screen by hand. Hand work is expensive and 20 slow and more or less inaccurate in accomplishing the desired result.

The object of my invention is to provide a machine by which to effectively and efficiently apply fluids through stencils to various materials 25 or stock. Other objects and advantages will appear hereinafter.

The invention is illustrated in the accompanying drawings in which

Figure 1 is a side elevational view of a machine 30 embodying the invention.

Fig. 2 is a rear end elevational view of the machine.

Fig. 3 is a plan view of the machine.

Fig. 4 is a cross-section on line 4—4 of Fig. 2 35 illustrating the stock gripper in releasing position.

Fig. 5 is an elevational view in enlarged scale of one of the gripper bars.

Fig. 6 is a cross-section on line 6—6 of Fig. 5 40 and

Fig. 7 is a side elevational view of the feed table.

Referring to the illustrative drawings, 1 is the frame consisting, in the present exemplification, of the uprights 2 and the side members 45 3 which support the top 4. An opening 5 is formed in the top in which a platen 6, normally below the top, is adapted to seat with its top face flush with the adjacent surface of the top 4. The platen is hinged at 7 to the upper side members 50 3.

Two chains 8, 9 respectively engage the sprockets 10, 11 mounted on the shaft 12, and they also engage two sprockets 13 on the shaft 14 supported at the forward end of the frame. Each chain 55 also engages an idler sprocket 15. A pinion 16

secured to the shaft 12 meshes with a gear 17 secured to the shaft 18 upon which shaft an intermittent gear 19 is rigidly mounted. An intermittent gear 20 meshes with the gear 19 and with an intermittent gear 21. The gear 20 is 5 secured to the shaft 22 that leads from a suitable differential 23 to which the drive shaft 24 is connected. The drive shaft is driven in suitable manner, as by an electric motor 25.

A cam 26 on the shaft 22 is engaged by an arm 10 27 that is secured to a rock shaft 28 adapted to rock the arms 29 that are pivoted respectively to the links 30. The links 30 are pivoted to a rod 31, and the links 32 are pivoted to this rod and to the lower side of the platen 6 by all which 15 the platen is intermittently raised and lowered on its hinges 7.

A series of transverse gripper-carrying bars 33 is carried by the chains. Each bar is suitably attached at its opposite ends to the two chains 20 and the spacing between the bars is such that the sheet 34 of the stock upon which the stenciling material is to be applied may be engaged by the bars successively without overlapping one another. Each bar, Figs. 4, 5, supports a suitable number of grippers 35, three such being shown. Each gripper consists of a tapered finger 36 loosely keyed to the revolvably mounted shaft 37 so that it may accommodate varying thicknesses or irregularities in the stock 34. A spring 30 38 opposes this accommodation movement of the gripper. A finger 39 is secured to the shaft 37 and depends therefrom. This finger, when it contacts a cam 40 on the shaft 12 rocks the shaft 37 and thereby elevates all the grippers to release the imprinted sheet 34. Also when it contacts a cam 41 secured to the shaft 42 adjacent to the feed board 43, the grippers are opened to receive a sheet 34.

A link 44 is eccentrically pivoted to the gear 40 17 and at its lower end it is pivoted to a shoe 45 that is slidably mounted on an arm 46 that is pivoted at its lower end to a crank 47 secured to the shaft 48. A link 49 is pivoted to the crank 47 and eccentrically pivoted to the intermittent 45 gear 21. An arm 50 is pivoted to a crank 51 secured to the opposite end of the shaft 48 on the opposite side of the machine. The links 52, 53 are pivoted to the arms 46, 50 respectively and extend forwardly, their forward ends being loosely 50 mounted on the spindles 54, 55 respectively which engage respectively in the lower ends of the end members 56, 57 of the squeegee carriage 58.

A rod 59 is attached at its lower end to the shoe 45 and a rack 60 is secured to the upper end 55

of the rod. The rack slides in the guide bracket 61 which is secured to the arm 46 and the rack engages a gear 62 mounted on a shaft 63 supported by the bracket 61. A rod 64 is connected at one end to the shaft 63 by a universal coupling 65, a similar coupling 66 connecting the rod 64 to a shaft 67 carried by the bearing 68 mounted on the link 52. A pinion 69 on the shaft 67 meshes with a segment gear or rack 70 that is secured to the spindle 54.

The squeegee carriage 58 consists of the end members 56, 57 and the cross member 71, having a suitable weight 72 thereon, fixed to the upper ends of said members. Two squeegees 73, 74 are adjustably mounted on the cross member 71 by the collars 75, 76, the squeegees being set at a selected angle to each other. The lower edge of each squeegee is adapted to bear upon the screen 77 which is temporarily fixed in proper position on the top 4. The carriage pivots on the spindles 54, 55 so that either squeegee may be engaged on the screen. The intermittent gears 17, 21 are so timed in their rotation that the link 49 and bell crank 47 will cause the arms 46, 50 to swing and draw the squeegee over the screen. The stenciling material, such as paint, is deposited on the screen preferably beyond the pattern, that is, in the position where the squeegee is at the end of its stroke. The gear 19 is so formed and set that the link 44 will cause the rack carrying rod 59 to reciprocate and cause the pinion to rotate and swing the segment gear 70 which in turn swings the carriage so as to engage the other squeegee on the screen. In Fig. 1 the carriage has completed its forward stroke. At the time the next sheet of stock 34 is in position for receiving the impression the rack bar 59 will ascend and the pinion 69 will cause the rack 70 to rock the carriage, causing the squeegee 73 to rise and the squeegee 74 to contact with the screen. The arms 46, 50 immediately thereafter cause the carriage to move to the left or rearwardly.

45 Two spindles 78, 79 are fixed to the end members 56, 57, respectively, of the carriage 58 and the rollers 80 are mounted on the spindles. These rollers are adapted to engage the rails 81 which are mounted adjacent to the upper frame members 3 for longitudinal and upward movement. 50 Normally the rollers do not engage the rails. The rails afford means by which to elevate the carriage and the squeegee when necessary or preferable to prevent forcing the stenciling material through the screen, as where a sheet fails to reach the stenciling station or is not registering properly at said station. The means for moving the rails comprises two levers 82 that are suitably pivotally mounted on the hangers 83 depending from the upper frame members 3 and pivotally connected at their upper ends to the 55 rear ends of the rails. A link 84 is pivoted at one end to one of the levers 82 and at its opposite end it is pivoted to a hand operated lever 85 that is pivotally mounted on one of the uprights 60 65 2. By rocking the long arm of the lever 85 downwardly the short arm thereof causes the levers 82 and the rails to swing upwardly and longitudinally. The rear end of each rail is bevelled as shown at 83, Fig. 1 and said end engages a sloping surface arranged adjacent to the frame member 3. The rails as they rise engage the rollers 80 and elevate the carriage and the squeegee is thereby withdrawn from the stenciling material on the screen. 70

75 The platen 6 is also lowered at the same time

that the rails are elevated. This is accomplished by the rod 86 that is connected to the rod 31 of the platen elevating devices. The opposite end of the rod 86 is pivoted to one arm of a bell crank 87 pivoted at 88 to the frame member 2. A link 89 is pivoted to the other arm of the crank 87 and to the lower end of the hand operated lever 85. When the lever 85 is rocked as before described, the rod 86 draws the rod 31 forwardly or toward the bell crank 87 thereby swinging the links 30, 32 forwardly to shorten the link distance between the lever 29 and the platen. The platen thereupon swings downwardly on its pivots and carrying the sheet 34 with it if one such is on the platen.

A shaft 90 is connected to the differential 23 and is connected to a bevel gear 91 that meshes with a bevel gear 92 secured to the lower end of the shaft 93 suitably revolubly mounted on the main frame. A bevel gear 94 on the upper end of the shaft 93 meshes with a bevel gear 95 secured to the shaft 42 to which shaft the cam 41 is secured. A second cam 96 is secured to the shaft 42 upon which bears a roller 97 mounted on a lever 98 that is secured to the shaft 99. A spring 100 tends to retain the engagement of the roller with the cam. The levers 101, 102 are secured to the shaft 99 and pivoted to the lower side of the feed table 43, each lever having a right angular projection 103 extending under the said table. The shaft 90 is rotated at a predetermined speed and causes the cams 41, 96 to rotate at said speed. The cam 96 is so formed that it will intermittently permit the lever 98 to rock upwardly, under the influence of the spring 100, whereby the levers 101, 102 are rocked rearwardly to tilt the table 43, as shown in Fig. 7. The continued rotation of the cam 96 then depresses the lever 98 and the levers 101, 102 rock forwardly and not only return the table to a horizontal position but also move it longitudinally so that its free end will engage and line up the gripper bar 33 that by this time has come to rest in the loading position. The spring 104 assures contact of the bar with the guard 105 so that the bar is in proper loading position with respect to the guides 106, 107 that are adjustably mounted on the table 43. This movement of the table is desirable, since a bar 33 may not always stop at the correct point due to stretching of the chains 8, 9 or variations therein. Also the vertical movement of the table clears the gripper bar that is approaching the feeding station. The throw of the table 43 being uniform it will move any bar, that comes to rest short of the correct loading position, to that position and line it up, the slack in the chains permitting such movement.

In the correct loading position of the bar 33 a sheet of the stock is inserted under the grippers 35 which are elevated by the lug 39 having contacted the cam or abutment 41. The chains then carry the bar and its attached sheet 34 to the impression station under the screen, the sheet then contacting the inclined platen. The bar 33 is engaged in the offset 108 in the platen as the latter rises and is thereby lined up and the spring 109 moves the bar against the guard 110 so that the bar is properly located at the imprinting station. 60 65 70

Any suitable means to receive the imprinted sheet after it leaves the impression station will suffice. In Figs. 1 and 3, I show a roller 111 mounted on the shaft 112 upon which is engaged a belt 112 that also engages a roller 113 revolutely. 75

mounted on a shaft 113 carried by the main frame. The sheet, being held at one end by the grippers on the bar 33 that is moving it, will tend to sag or drop. The belt will support it and prevent its contact with any part of the machine, and when the grippers release it, the belt will convey it off the machine where it may be received or handled in any convenient manner.

What I claim is:

- 10 1. A machine of the class described comprising a stencil, means to support the stencil, a conveyor having a plurality of spaced gripper-carrying members thereon each member adapted to engage a sheet of the material to be treated and carry the same beneath the stencil, means to drive the conveyor intermittently, intermittently actuated means to support the material in contact with the lower side of the stencil and having means thereon to align the gripper bars relatively to the stencil reciprocable means to force an imprinting substance through the stencil on to the material, said reciprocable means including a pair of squeegees and means to alternately engage the squeegees on the stencil.
- 15 2. A machine of the class described comprising a stencil, means to support the stencil, a conveyor having a plurality of gripper-carrying members thereon, each said member being adapted to engage the material to be treated, means to intermittently drive the conveyor whereby each gripper is moved to a loading station, then to an imprinting station under the stencil and finally to a discharge station, means to open the grippers at the loading station and at the discharge station, means at the imprinting station to cause the material to firmly engage the bottom side of the stencil and adapted to align the gripper carrying member relatively to the stencil screen and reciprocable means to force an imprinting substance through the stencil on to the material said latter means including a squeegee carrier and means to intermittently reciprocate the carrier in opposite directions across the stencil.
- 20 3. A machine of the class described comprising a stencil screen, means to support the stencil screen, a conveyor having a plurality of gripper carrying-members thereon, means to intermittently drive the conveyor whereby the gripper-carrying members are successively moved to a loading station, to an imprinting station under the stencil screen and to a discharge station, a pivotally mounted feed table at the loading station adapted to engage and align each gripper carrying-member, means at the loading and the discharge stations to open the grippers, a platen hinged for movement toward and from the screen and adapted to align the gripper bars and a carrier having two squeegees thereon, means to intermittently reciprocate the carrier and means to rock the carrier at the end of each stroke thereof whereby to alternately contact the squeegees with the stencil screen.
- 25 4. A machine of the class described comprising a frame, a top carried by the frame and having an opening therein, a stencil screen secured to the top and extending across the opening, a platen hinged to the frame below the top and adapted to be swung upwardly to close the said opening, a pivotally mounted feed table at the forward end of the frame, an endless conveyor having thereon a plurality of transverse gripper-carrying bars, means to drive the conveyor intermittently whereby the said bars are moved in succession to loading position adjacent to an end

of the feed table and are engaged and aligned by said table, the next stage of movement of the conveyor carrying the bars loaded with the product to be treated successively above the platen to an imprinting station, means to rock the platen upwardly to engage the product on the bottom of the stencil screen, a squeegee carrier, means to reciprocate the carrier, means to rock the carrier at the end of each reciprocation whereby to contact a squeegee with the stencil screen.

5 5. In a machine of the class described the combination with a stencil screen, a substance on the screen suitable for stenciling and means to successively support sheets of material to be stenciled in contact with the screen, of means to force the substance through the screen and consisting of a carrier, two squeegees on the carrier, means to move the carrier to and fro and means having connection with the carrier to rock the carrier for alternate gravitational engagement of the squeegees with the screen whereby to force the substance through the screen onto a sheet of material during each movement of the carrier.

10 6. In a machine of the class described the combination with a stencil screen and means to successively support material to be treated in contact with the lower surface of the screen of means to force through the screen a substance deposited thereon and adapted to pass through the same, comprising a carrier having two oppositely inclined squeegees thereon adapted to alternately engage the screen under the influence of gravity, intermittently actuated rocking members having connection with the carrier for moving it back and forth, a reciprocable member carried by one of the rocking members and having a connection with the carrier to intermittently rock the carrier and alternately contact the squeegees with the screen and force the said substance through said screen onto the material during each movement of the carrier.

15 7. In a machine of the class described, the combination with a stencil screen, and means to successively support sheets of material to be stenciled in contact with the stencil screen, of means to force an imprinting material through the screen and comprising a cross member, two oppositely inclined squeegees mounted on the cross member, and depending members rigidly connected to the opposite ends of the cross member, spindles rigidly engaged in the end members and means connected to the spindles for reciprocating the cross member and to cause the squeegees to alternately engage the screen.

20 8. In a machine of the class described, the combination with a stencil screen, and means to successively support sheets of material in contact with the screen, of means to force imprinting material through the screen and comprising a cross-member two oppositely inclined squeegees mounted on the cross-member, end members attached to the opposite ends of the cross-member respectively, and depending therefrom, spindles projecting laterally from the end members respectively a pair of rocker arms, means to rock said arms intermittently in opposite directions, links pivotally connected to the rocker arms and to the spindles respectively, a rack mounted on one of the spindles and means to oscillate the rack intermittently in opposite directions to cause the squeegees to be alternately presented to the imprinting material.

25 9. In a machine of the class described, the combination with a stencil screen and means to support sheets of material in contact with the

30 35 40 45 50 55 60 65 70 75

screen, of an intermittently driven conveyor to carry the sheets to and from the support successively, and a tilting feed table adjacent to the conveyor on which the sheets are fed successively to the conveyor.

5. 10. In a machine of the class described the combination with a frame, stencil screen attached to the frame, a platen hinged to the frame below the screen, an intermittently operated conveyor to carry sheets of material successively onto and

10

from the platen, intermittently operated means to rock the platen toward the screen for contacting the sheets with the screen, means to apply a stenciling substance through the screen and onto the sheets, a hinged feed table adjacent to the carrier on which the sheets are fed successively to the carrier and means to intermittently swing the table into alignment with the conveyor. 5

JESSE D. KLOPFENSTEIN.
